UNITED STATES PATENT OFFICE.

OMAR M. CURTIS, OF WOLCOTT, NEW YORK.

FURNACE.

SPECIFICATION forming part of Letters Patent No. 682,673, dated September 17, 1901.

Application filed November 12, 1900. Serial No. 36,275. (No model.)

To all whom it may concern:

Be it known that I, OMAR M. CURTIS, a citizen of the United States, residing at Wolcott, in the county of Wayne and State of New 5 York, have invented a new and useful Furnace, of which the following is a specification.

My invention is an improved furnace for evaporating fruit and drying hops; and it consists in the peculiar construction and combination of devices hereinafter set forth, and 10 pointed out in the claims.

One object of my invention is to improve the construction of the top of the furnace, so that pieces of fruit or hops which may drop 15 thereon from the drying-rack above the furnace will not lodge on the top of the furnace and become burned, and thereby create an injurious smoke and smell.

A further object of my invention is to improve 20 the construction of the fire-pot, so that the same is rendered more durable.

A further object of my invention is to effect improvements in the construction and combination of the jacket of the furnace and 25 the frame of the feed-door to more securely fasten the feed-door frame to the furnace.

A further object of my invention is to effect improvements in the construction of the feed-door, so that the same is provided with 30 an interior lining and an air-space between the lining and the feed-door to screen the latter from the directly-radiated heat.

A further object of my invention is to provide improved means to lock the grate in a 35 horizontal position and prevent the same from being dumped.

In the accompanying drawings, Figure 1 is a perspective view of an evaporating and drying furnace embodying my improvements. 40 Fig. 2 is a vertical central sectional view of the same. Fig. 3 is a horizontal sectional view of the same, taken on a plane indicated by the line *a a* of Fig. 2. Fig. 4 is a similar view taken on a plane indicated by the line 45 *b b* of Fig. 2.

My improved furnace comprises the base-section 1, the fire-pot 2, the jacket 3, and the top 4. The base-section 1 is provided on its front side with the frame 5 for the ash-door 50 6, and in the upper side of the base is an annular groove 7, which receives the lower side of the fire-pot 2. The said fire-pot is cast in

a single piece and is of inverted truncated conical form and has in its upper side an annular groove 8, which receives the lower edge 55 of the jacket 3 and enables a cemented joint to be formed in the said groove to prevent the escape of gas from the joint between the said fire-pot and the said jacket. The latter is provided in its front side with a countersink 60 9, extending around the opening 10, for the feed-door frame. The said feed-door frame 11 has a flange 12 extending from the sides thereof and from its upper and lower side, the said flange 12 fitting in the said counter- 65 sink 9 and the lower side of said flange 12 fitting in the groove 8 in the upper side of fire-pot 2. The feed-door 13, which is hinged to the frame 11 in the usual manner, is provided on its inner side with a lining-plate 14, which 70 is offset around its edges, as at 15, and thereby an air-space is formed between the said feed-door and said lining-plate. The latter and the said air-space serve to protect the feed-door from the directly-radiated heat 75 from the interior of the furnace, thereby preventing the door from warping and prolonging the life thereof. The top 4 of the furnace is provided with the usual flanged openings for the attachment of the smoke and radiating pipes, said openings being indicated at 16. The said top 4 is rounded or of concavo-convex form and is adapted thereby to shed by gravity pieces of fruit or hops which may fall thereon from the drying rack or floor 80 85 above the furnace, thereby preventing the same from lodging and burning on the furnace-top and emitting smoke, which is injurious to the fruit or hops in process of evaporation or drying. The top 4 is provided on its under side with an annular groove 90 95 17, which fits on the upper side of the jacket-section 3 and also receives the upper side of the feed-door frame.

It will be understood from the foregoing 95 that the feed-door frame, which is set in the countersink 9 of the jacket-section 3, has its upper and lower sides fitted, respectively, in the grooves 17 of top 4 and the groove 8 of the fire-pot, and hence the connection between the said feed-door frame and the jacket-section of the furnace is strengthened, and the feed-door frame is prevented from dropping when the bolts 18, which also secure the 100

same to the jacket-section of the furnace, are burned off.

The grate 19 is pivoted centrally on the grate-bar 20, which grate-bar has trunnions 21 at its ends which engage suitable sockets 22, formed in the sides of the base-section 1. The said grate-bar is disposed at right angles to a plane intersecting the ash-door 6, and thereby the grate is adapted to be tilted and caused to dump to the front toward the said ash-door. When the grate is in a horizontal position, the ear 23 on the front side thereof bears under the flange formed by the base-section 1 above the opening of the ash-door. In order to prevent the grate from dumping itself, I provide a locking-bolt 24, which is secured in a horizontally-disposed guideway 25, formed in the base-section 1 above the door 6. The inner end of the said locking-bolt when the same is pushed in, as shown in Figs. 2 and 4, bears under the front side of the grate and prevents the latter from dumping. When the locking-bolt is drawn outward, so as to cause the inner end thereof to disengage the grate, the latter may be

readily dumped, as will be understood. The ear 23 of the grate has an opening 23^a for the reception of the inner end of a bar or lever for shaking and dumping the grate.

Having thus described my invention, I claim—

The combination of a fire-pot having a groove in its upper side, a jacket-section having its lower side fitted in said groove, said jacket-section having an opening for a feed-door, and an offset or countersink around said opening, a top having a groove in its lower side, to receive the upper edge of said jacket-section, and a feed-door frame having a flange fitted in said countersink or offset, the upper and lower edges of said flange engaging said grooves in said top and in said fire-pot, substantially as described.

In testimony that I claim the foregoing as my own I have hereto affixed my signature in the presence of two witnesses.

OMAR M. CURTIS.
